US0D1035616S

(12) **United States Design Patent** (10) **Patent No.:** **US D1,035,616 S**
(45) **Date of Patent:** ** *Jul. 16, 2024

(54) **SPEAKER**

(71) Applicant: **Logitech Europe S.A.**, Lausanne (CH)

(72) Inventors: **Pontus Wahlgren**, Lausanne (CH);
Doug Ebert, Portland, OR (US); **Don Mayette**, Lausanne (CH); **Dominic Amae**, Vancouver, WA (US)

(73) Assignee: **Logitech Europe S.A.**, Lausanne (CH)

(*) Notice: This patent is subject to a terminal disclaimer.

(**) Term: **15 Years**

(21) Appl. No.: **29/764,538**

(22) Filed: **Dec. 30, 2020**

Related U.S. Application Data

(60) Continuation of application No. 29/712,561, filed on Nov. 8, 2019, now Pat. No. Des. 909,340, which is a division of application No. 29/599,552, filed on Apr. 4, 2017, now Pat. No. Des. 871,371.

(57) **CLAIM**

The ornamental design for speaker, as shown and described.

DESCRIPTION

FIG. 1 is a perspective view of a speaker showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The broken lines shown to be immediately adjacent to the shaded/contoured areas represent certain portions of the bounds of the claimed design while all other broken lines are directed to environment and are for illustrative purposes only. The broken lines form no part of the claim design.

1 Claim, 4 Drawing Sheets
